SOLENOID DIPPER TRIP

Filed Aug. 5, 1929

Attorneys

UNITED STATES PATENT OFFICE

EDGAR H. TELLIER AND ROBERT C. DECKMAN, OF MILWAUKEE, WISCONSIN, ASSIGNEES
TO KOEHRING COMPANY, OF MILWAUKEE, WISCONSIN, A CORPORATION

SOLENOID DIPPER TRIP

Application filed August 5, 1929. Serial No. 383,504.

Power means for tripping the door of a dipper in an excavating machine has been used for a considerable period of years. However, several difficulties have arisen in this connection.

It is understood by those skilled in the art that the dipper and associated dipper stick are continually changing their position in respect to the boom of an excavating machine. If the power means is located on the boom of the machine, it is necessary to devise some type of flexible power transmission from the power means to the latching mechanism of the door in order to accommodate this change of position of the dipper in respect to the boom. Likewise, if the power means is mounted on the dipper stick, it is necessary to provide a flexible motive force for this power means since the source of power in practically every case is located on the body of the excavating machine.

The object of our invention, therefore, is to provide novel mechanism for transmitting power to a power means on the dipper stick which mechanism will adapt itself to the varying positions of the dipper stick with respect to the boom.

In the instant construction or embodiment of our invention we make use of an electrical dipper tripping mechanism mounted on the dipper stick. The cable for supplying energy to this electric dipper trip is wound on a reel which is in turn actuated by the racking in and crowding out mechanism of the excavating machine. Because of this construction the cable is wound and unwound as the dipper is racked in and crowded out, thereby providing for flexibility in the power transmission means. Novel devices for supplying an electrical current to this cable are also provided.

A further object of the invention is the provision of a tensioning means independent and separate from the aforesaid reel by means of which the cable is kept taut at all times.

Another object of the invention is the provision of a novel linkage between the electrical devices and the dipper latching mechanism. The links are so constructed or assembled that the initial movement thereof is

unrestricted, thereby allowing the power means to gather a certain amount of velocity or momentum, which, upon further movement of said power means is given up in delivering a quick snatching action to the latching mechanism. This insures a more positive and more efficient operation of the latching mechanism.

Further objects of our invention will become apparent as the description thereof proceeds.

For a full and more complete understanding thereof, reference may be had to the following description and accompanying drawings, in which—

Figure 1 is a side view of those parts of an excavating machine with which my novel invention is associated and shows the same applied thereto.

Figure 2 is a perspective view of the reel upon which my cable is wound and has parts broken away to more clearly bring out the construction thereof.

Figure 3 is a view taken about on the line 3-3 of Figure 1 and shows the association of the reel with the racking in and crowding out mechanism, and

Figure 4 is a perspective view of a modified form of reel construction.

While a preferred specific embodiment of our invention is herein set forth, it is to be understood that we are not to be limited to the exact constructions illustrated and described, because various details of these constructions may be modified within the purview of the appended claims.

Referring particularly to Figure 1, a portion of the boom of an excavating machine is represented at A which boom is provided with the usual dipper stick B, dipper C having a door D, and any suitable type of latching mechanism therefor, not shown. The shipper shaft of the racking in and crowding out mechanism is shown at E.

A solenoid 1 comprising a coil 2 and armature 3 is secured to the dipper stick B by any suitable means such as the brackets shown at 4. The ends of the coil 2 are formed with connecting terminals denoted 5 and 6. One end of an operating member

7 is pivotally connected at 8 to bracket 9 which in turn is secured to the dipper stick B. The other end of this operating member 7 is connected to that end of the armature 3 which extends beyond the coil 2 by means of a link 10. A second link 11 is pivotally secured to the operating member 7 at any suitable point between the ends thereof and denoted 12. A chain 13 loosely connects the link 11 to the latching mechanism. It will readily be understood, therefor, that movement of the armature 3 in the coil 2 is free and unrestricted at the initiation of such movement. The armature 3 will therefore develop a high velocity and momentum. Upon further and continued movement of this armature 3 the chain 13 will become taut and this aforementioned velocity and momentum will thereupon be delivered to the unlatching mechanism with a quick snatching action, thereby insuring positive and efficient operation thereof.

The manner in which electrical energy is supplied to the coil 2 of the solenoid 1 will now be described. The terminal 6 of the coil 2 is grounded to the dipper stick at any convenient point such as 14. A cable 15 having one end secured to the terminal 5 is threaded through the eye 16 of an elastic insulating member 17, preferably made of rubber, the other end of which is secured to the dipper stick B by means of a bracket 18. The cable 15 is then brought up to a reel 19 which in turn is secured to the shipper shaft E. In the preferred form the reel 19 has secured thereto a ring 20 made of any suitable material for properly conducting an electrical current. This ring 20 is insulated from the reel 19 by insulation material 29, ring 20 serving as a current collector, the insulation 29 preventing flow of current through the reel 19. The cable 15 is wound about the reel 19 a suitable number of times and the end of said cable is passed through openings 21 in the reel 19 and then secured to the ring 20 as at 22. Another cable 23 has one end suitably connected to a power source not shown, the other end being connected to a brush 24 which is positioned to engage and contact the ring 20. The other connection of the power source is grounded as will be readily understood. It can thus be seen that the solenoid is energized from a power source located on the body of the excavating machine by means of a cable which is wound and unwound as the dipper stick is racked in and crowded out.

The tensioning means 17 is provided so that the cable 15 will be taut at all times, even if the same should become stretched or deformed during operation of the machine. As before pointed out, this member 17 is preferably made of an insulating material such as rubber to guard against any possibility of a short circuit.

In Figure 4 a modified form of reel has been shown. In this construction the cable 15 is wound about a reel 25, the end of the cable 15 being directly secured thereto as shown at 26. A bushing 27 of any suitable insulating material is interposed between the reel 25 and the shipper shaft E, thereby insulating these parts one from another. The bushing 27 may be provided with projections or lugs 28 so as to form a positive connection with the reel 25. In this construction it is unnecessary to insulate the cable 15, and brush 24 may bear directly against the reel 25, thereby eliminating the necessity of the ring 20 as above described.

Having thus described our invention, what we claim as new and desire to secure by Letters Patent of the United States, is—

1. In dipper tripping mechanism for excavating apparatus, the combination with a dipper having a door latching mechanism, and shiftable supporting means therefor, of an electric actuating unit for said latching mechanism and carried by said supporting means, an electric conductor connected at one end to a suitable source of current supply and at the other end to said unit, and elastic, insulating slack take up means cooperating with said conductor to maintain slack take up of the same during shifting of the supporting means.

2. In dipper tripping mechanism for excavating apparatus, the combination with a dipper having a door, latching mechanism therefor, and a support for the dipper, of an electric actuating unit for said latching mechanism, an electric conductor cable connected at one end to said unit and at the other end to a suitable source of current, devices for shifting the dipper in respect to the support, insulated winding means for reeling the conductor cable and controlled by said devices and a yieldable insulating slack take up means, both of said means coacting with said conductor cable to maintain the same in a taut condition.

3. In dipper tripping mechanism for an excavator, the combination with a boom, a dipper stick, a dipper having a door, latching mechanism therefor, and means including a shipper shaft for racking in and crowding out the dipper stick, of an electrical operating means on the dipper stick for operating said latching mechanism, a cable connected to said electrical operating means for supplying electrical energy thereto, means carried by the shipper shaft for winding and unwinding said cable as the dipper stick is racked in and crowded out, the said means being provided with insulation to prevent flow of current therethrough and a resilient member of insulating material separate from said last named means for tensioning said cable.

4. In dipper tripping mechanism for an

excavator, the combination with a dipper having a door, latching mechanism therefor, and a support for the dipper, of a solenoid for actuating the latching mechanism, means 5 comprising a current conducting cable for supplying electrical power to said solenoid, a slack connecting means connecting said unit to said latching mechanism whereby initial movement of said unit is unrestricted to 10 allow the same to accumulate momentum for delivering a quick snatching action to the latching mechanism, and an elastic insulating member for maintaining the said cable taut under all conditions of operation.

15 5. Dipper trip mechanism comprising a dipper stick, a dipper having a door, latching mechanism therefor, a solenoid including an armature, a member pivoted to the dipper stick and connected to the armature of the 20 solenoid, a slack operating means connecting said member to the latching mechanism, and means comprising a current conducting cable for energizing the solenoid to cause movement of the armature, and electrically insulated means for maintaining the said cable 25 taut under all conditions of operation.

6. In a shovel, a boom, a dipper stick, a dipper having a door, latching mechanism therefor, an electrical device carried by the 30 dipper stick, means operatively connecting said device to the latching mechanism, means for racking in and crowding out the boom, a reel operated by said last named means, means for electrically energizing said device 35 including a ring carried by said reel, a brush contacting with said ring, a conducting cable having one end electrically connected to the solenoid and the other end wound about said reel and secured to said ring, a second cable 40 connected to the said brush and to a source of current for conducting the current from the said source to the cable leading to the solenoid, and a rubber member secured to the dipper stick and to the said cable leading 45 to the solenoid for maintaining the said cable taut under all conditions.

In testimony whereof we affix our signatures.

EDGAR H. TELLIER.
ROBERT C. DECKMAN.
